his Attorney

UNITED STATES PATENT OFFICE.

WILLIAM GRIEST, OF FRANKLIN, OHIO.

BUCKLE.

No. 808,538.

Specification of Letters Patent.

Patented Dec. 26, 1905.

Application filed April 10, 1905. Serial No. 254,692.

To all whom it may concern:

Be it known that I, WILLIAM GRIEST, a citizen of the United States, residing at Franklin, in the county of Warren and State 5 of Ohio, have invented certain new and useful Improvements in Buckles, of which the following is a specification.

My invention pertains to harness-buckles, more particularly buckles for holding the opposite ends of a strap when the same is used 10 to form a harness-loop; and it is designed more particularly as an improvement upon the subject-matter of my Letters Patent No. 777,627, of December 13, 1904.

15 The novelty, utility, and practical advantages of the present invention will be fully understood from the following description and claims when taken in connection with the accompanying drawings, forming part of 20 this specification, in which—

Figure 1 is a perspective view of my improved buckle. Fig. 2 is a longitudinal central section taken through the buckle and a strap properly positioned therein. Fig. 3 is 25 a transverse section taken in the plane indicated by the line 3 3 of Fig. 2, and Fig. 4 is a perspective view of the lower body-section of the buckle removed.

Similar letters designate corresponding 30 parts in all of the views of the drawings, referring to which—

A is a looped strap having holes a, and B, C, and D are the lower body member, the upper body member, and the tongue, respectively, of my novel buckle. The lower body member B is cast or otherwise formed of metal or other material suitable to the purpose and comprises an intermediate plate b, having a central aperture c and depending 35 studs d and also having upwardly-extending transversely-apertured lugs e and end loops f, which are wider than the intermediate plate, so as to provide shoulders g, and are deflected downwardly from the ends of said 40 plate, as shown, for a purpose presently set forth. The upper body member C is preferably of the same material as the lower member B and has side bars h, arranged at the 45 outer sides of the lugs e and curved in the direction of their length, so as to present convex edges to the shoulders g of member B, and end bars i, one of which is preferably, 50 though not essentially, equipped with an antifriction-barrel k. The two members B and C are pivotally connected through the 55 medium of a transverse pintle l, which ex-

tends through the side bars of the latter and the lugs e of the former and serves also for the pivotal connection of the tongue D, the eye of which rests in the aperture c of plate v, 60 this with a view of permitting of the parts being arranged close together, and thereby contributing to the compactness of the buckle as a whole.

It will be apparent from the foregoing that 65 the member C is free to rock longitudinally on the member B, so as to facilitate placing the strap in engagement with both members, and that such rocking movements of the member C are limited by the shoulders g of 70 member B, which shoulders support and reinforce the member C when the loop of the strap A is subjected to pull, and thereby contribute materially to the strength and durability of the buckle as a whole. 75

The strap A is preferably arranged, as shown in Figs. 2 and 3, relative to the buckle—that is to say, the strap is looped, as indicated by m, and one of its end portions is passed through one end loop of body member B and 80 placed in engagement with the studs on the intermediate plate of said member, while its other end portion is passed through one end of the body member C and engaged with the tongue D, after which it is passed through 85 the opposite end of member C and the other end loop of member B and placed in engagement with one or both of the studs. In this way it will be observed that both ends of the straps are secured and the finished appearance 90 of the piece of harness thereby enhanced, and it will also be observed that a short piece of strap may be used to form two loops, one at each end of the buckle.

I have specifically described the construction and relative arrangement of the parts comprised in the buckle constituting the present embodiment of my invention in order to impart a definite understanding of the embodiment; but I do not desire to be understood as confining myself to the same, as such changes or modifications may be made in practice as fairly fall within the scope of my invention as claimed. 95

Having thus described my invention, what 100 I claim as new, and desire to secure by Letters Patent, is—

1. A buckle comprising reversely-curved body members opposed to and arranged to rock upon each other; one of said members 105 having intermediate shoulders for limiting the rocking movements of and reinforcing

the other, means connecting the members and permitting the rocking movements thereof, and strap-holding means carried by the members.

- 5 2. A buckle comprising reversely-curved body members opposed to and arranged to rock upon each other; one of said members having an intermediate portion bearing strap-holding means and side lugs and also having 10 end loops of greater width than the intermediate portion, whereby shoulders are formed, and the other member having side bars arranged alongside said lugs, a transverse pintle pivotally connecting said lugs and side 15 bars, and a tongue mounted on the pintle.
3. In a buckle, the combination of reversely-curved body members opposed to and ar-

ranged to rock upon each other; one of said members comprising an intermediate plate having a central aperture and side lugs, and 20 end loops of a greater width than the intermediate plate, and the other member comprising side bars and end bars, a pintle pivotally connecting the said lugs and side bars of the members and a tongue having an eye receiving the pintle and disposed in the aperture of the intermediate plate.

In testimony whereof I affix my signature in presence of two witnesses.

WILLIAM GRIEST.
